UNITED STATES PATENT OFFICE

160,819

COMPLEXION CREAM JAR

Lawrence H. Singer, Brooklyn, and Evelyn M. Corper, Garden City, N. Y., assignors to Conti Products Corporation, Brooklyn, N. Y., a corporation of New York

Application October 20, 1949, Serial No. 5,592

Term of patent 3½ years

(Cl. D53—25)

To all whom it may concern:

Be it known that we, Lawrence H. Singer and Evelyn M. Corper, citizens of the United States, residing respectively at Brooklyn, in the county of Kings and State of New York, and at Garden City, in the county of Nassau and State of New York, have invented a new, original, and ornamental Design for a Complexion Cream Jar, of which the following is a specification, reference being had to the accompanying drawings, forming a part thereof.

We claim:

The ornamental design for a complexion cream jar, as shown.

LAWRENCE H. SINGER.
EVELYN M. CORPER.
